UNITED STATES PATENT OFFICE

2,462,959

HAMMER

Paul C. Hardy, Portland, Oreg.

Application July 30, 1945, Serial No. 607,862

1 Claim. (Cl. 306—42)

1

This invention relates generally to tools and particularly to a hammer.

The main object of this invention is to provide a special form of soft-faced hammers in which the striking faces may be easily removed or substituted and in which various kinds of striking faces can be employed without difficulty.

The second object is to provide an improved form of fastening whereby the hammer head is securely mounted on the handle, the removable end held in place by a single fastening screw.

The third object is to construct a hammer in the class described in which the balance of the hammer is maintained, and in which the parts lend themselves to reproduction by die-casting methods.

I accomplish these and other objects in the manner set forth in the following specification as illustrated in the accompanying drawing, in which:

Fig. 1 is a side elevation of the hammer with the handle thereof broken away.

Fig. 2 is an end elevation of Fig. 1.

Fig. 3 is a plan of the hammer with the cap and clamping screw removed.

Fig. 4 is a plan of the assembled hammer.

Fig. 5 is a vertical section taken along the line 5—5 in Fig. 4.

Fig. 6 is an end elevation of Fig. 5 with the striking element removed.

Similar numerals refer to similar parts throughout the several views.

Referring in detail to the drawing, there is shown a semi-cylindrical hammer body 10 having a shank 11 extending from the rounded portion thereof. The shank 11 is provided with a tapered recess 12 for the reception of the handle 13. The innermost end 14 of the recess 15 is tapered in the opposite direction than is the portion 12, in order to receive the spread portions 15—A of the handle 13 as produced by the wedge 16.

Mounted on the body 10 is a cap 17 which is also semi-cylindrical although it is preferable to make the body 10 and cap 17 slightly larger at the intermediate point 18. Between the members 10 and 17, and at each end thereof, are formed the counter-bored recesses 19 in which may be disposed the button-heads 20 formed on the shanks 21 of the cylindrical striking head 22.

The striking head 22 may be of rubber, wood, composition, or hard or soft metal, or any other desired material, without departing from the spirit of this invention.

In order to hold the members 10 and 17 to- 55

2

gether, there is provided a screw 23 whose end 24 bears against the wedge 16. The head 25 of the screw 23 occupies a recess 26 in the cap 17. It is desirable to employ a screw of the safety type as illustrated.

It can be seen from the foregoing, that from this simple arrangement, the striking elements 22 may be easily inserted or replaced, and are securely held by means of the single screw 23, which at the same time, holds end wedge 16 in place and preventing the accidental separation of the handle 13 from the hammer.

It is desirable to provide a tongue 26—A across the end groove 27 between the members 10 and 17 in order to protect the screw 23 and the parts 19 from the hammer action.

It can be seen that the side 28 of each recess 19 is inclined with relation to the axis of the hammer, the purpose being to insure a wedging action which will hold the inner edge 29 of the striking element 22 against the outer edges 30 and 31 of the members 10 and 17 respectively.

While I have thus illustrated and described my invention, I do not intend to be limited to such forms shown herein, but I do intend to cover all such forms and modifications thereof as fall fairly within the appended claims.

I claim:

30 A hammer consisting of a somewhat cylindrical head divided along a plane extending through its major axis, the parts having a transverse tongue and groove across said plane, one portion thereof having a handle socket formed therein provided with an enlarged interior, and the other portion of said head constituting a cap, including a clamp screw for securing said cap to the handle bearing member, a handle mounted in said handle socket having a wedge in the end thereof engaging said screw, and a pair of striking inserts adapted to be held by the halves of said head.

PAUL C. HARDY.
